DOOR CHIME AND CALL STATION
ANNUNCIATOR

William C. Gustin, Cincinnati, Ohio

Application May 7, 1946, Serial No. 667,819

8 Claims. (Cl. 177—339)

1

The present invention relates to door signal apparatus and has for an object the provision of a small, simple and inexpensively constructed push button casing for use at an entry door for actuating an interiorly disposed chime or the like, the push button casing containing an illuminable annunciator plate normally serving as a name card for the occupant and selectively arranged for electrical actuation to display "Out" signal.

A further object is to provide an arrangement wherein a device of this kind which is self-contained within the push button casing may be installed in an existing wiring system containing the usual door push button and interiorly disposed chime by substituting the push button casing assembly of the present invention for an existing one and by providing a manually operable cut-out switch on the existing chime device.

A further object of the invention is to provide a doorbell casing and assembly utilizing small and inexpensive parts.

Still another object of the invention is to provide door signal actuating means affording visible indicia, illumination thereof and audible signal at the door for the guidance of callers.

These and other important objects are attained by the means described herein and disclosed in the accompanying drawings, in which:

Fig. 1 is a front elevational view of the push button device of the invention.

Fig. 2 is a rear elevational view of the device of Fig. 1.

Fig. 3 is a cross-sectional view taken on line 3—3 of Fig. 2.

Fig. 4 is a wiring diagram of a typical installation of a door signal system embodying the invention.

The push button casing indicated generally at 6 may be of any suitable construction and comprises a front wall 7, side walls 8 and 9, top wall 10 and a bottom wall 11. Walls 10 and 11 may have extended flanges 12 perforated at 13 for the reception of mounting screws. The hollow interior of the casing is quite shallow and narrow and the height thereof need be only about three times the diameter of the conventional doorbell push button switch. It will be apparent therefore that the device is quite small and neat, and may be made to occupy an area at the side of the door-frame comparable to the average push button casing of the type adapted for the reception of a name card. Front wall 7 has a circular perforation 14 therethrough centrally disposed closely adjacent bottom wall 11. A push button switch assembly 15 is mounted in the

2

casing through aperture 14 in conventional manner and is of the simple type having two terminals 16 and 17. Directly above push button switch 15 is a horizontal member 18 which may incidentally constitute a lateral strengthening member for casing when the latter is formed of thin sheet metal. On the lower face of top wall 10 is a depending lug 19 from which a small solenoid assembly 20 is suspended from its top bracket 21 by means of screws 22. A transverse window slot 23 is formed in the front 7 of casing 6. Internally below the window 23 and alongside solenoid 20 there is supported a miniature lamp socket 24 in which is a small-sized, low voltage glow lamp 25. Solenoid 20 has a light, cylindrical armature 26 to the bottom of which is riveted a non-magnetic, light-weight L-shaped plate 27, the major portion 28 of which lies parallel with and closely adjacent the inside face of front wall 7 of casing 6. The riveted end of the armature 26 normally rests on horizontal member 18 when the solenoid is de-energized. The non-magnetic plate 28 covers window 23 in the front wall of the casing and is provided at 29 with cut-out letters spelling the occupant's name. The cut-out or indicia 29 registers with the window 23 when the solenoid is de-energized. Immediately below the indicia 29, the plate has stamped therethrough the indicia 30 spelling the word "Out." When solenoid 20 is actuated the plate 28 is raised to display the word "out" and conceal the indicia 29.

Reference is now made to Fig. 4 wherein the door signal chime mechanism is indicated at 31, this being understood to be suitably located interiorly of the house or apartment. A suitably located, low voltage transformer 32 having output terminals 320 and 321, has its terminal 320 connected to terminal 33 of the chime mechanism 31 by a conductor 34. The remaining terminal 35 of the chime mechanism is connected by conductor 36 to one end of the winding of solenoid 20, while the opposite end of said winding leads to terminal 17 of the push button switch through conductor 37. A branch conductor 38 connects conductor 37 with one terminal of the glow lamp 25, while the opposite terminal of said glow lamp is connected to transformer terminal 320 by a conductor 39. Glow lamp 25 is desirably of the neon type operable by current alternations of low voltage. At this point it should be noted that in applying the device of the invention to an existing door signal system, the wire 39 or some equivalent electrical connection is required to be supplied if not otherwise available. The terminal

16 of push button switch 17 is connected with the terminal 321 of transformer 32 by connector 40. On the door chime structure 31 there is mounted an off-on pull type switch 41 (shown diagrammatically) which may be operable by an ornamental pull cord 42 for selectively connecting and disconnecting the terminals 33 and 35 through a movable switch arm 43.

When switch arm 43 connects terminals 33 and 35, closing of push button switch 15 will complete a circuit through the member 43 instead of through the chime mechanism, thereby rendering the chime inoperative. The resistance, particularly the usual chime solenoid (not detailed), being cut out of circuit, the solenoid 20 is energized thereby lifting armature 26 and raising plate 28 so that the legend "Out" is brought into registry with window 23, while the push button 15 is held in a circuit closing relation. The output of the transformer being of A. C. variety will effect, in the energized solenoid 20 and its armature, the usual chattering which serves as an audible sound to attract the attention of the user to the push button casing 6 and in doing so the legend "Out" is readily noted as it is exposed through window 23 at this time. The glow lamp 25 having its terminals connected in series in the closed branch circuit will afford sufficient illumination of the perforated legend to render it legible in darkness.

When the house occupant leaves the apartment, switch 41, which may be of a type commonly referred to as a canopy switch, is conditioned to cause the aforescribed performance and callers are forthwith apprised of the absence of the occupant when pressing the door chime push button switch 15. The chime is of course silenced by this arrangement and other apartment occupants are not annoyed by continued operation of the chimes in the apartment from which the occupant is absent.

When the occupant is at home the pull 42 is operated and switch 41 throws its switch arm 43 to the dotted line position in Fig. 4 whereupon actuation of switch 15 will provide a closed circuit in which the mechanism of chimes 31 is in circuit and providing a greater resistance in the circuit. Under these conditions solenoid 20 will be insufficiently energized to raise armature 26 and plate 28. Glow lamp 25 will again be energized to illuminate the exposed indicia 29. Thus the caller verifies the correctness of his signal at the same time the chime mechanism 31 is operating interiorly of the apartment.

The operativeness of a door signal system embodying the invention is assured in any normal installation due to the fact that the winding of solenoid 20 is of coarser wire and of fewer turns than will be found in the conventional chime solenoids or in electric door bells. These are usually arranged to operate on a transformer output of from four (4) to six (6) volts. Solenoid 20 being of lesser resistance than such chime mechanism as 31, said solenoid 20 is fully energized to lift plate 28 only when the greater resistance of the chime mechanism 31 is cut out of circuit by switch arm 43 or its equivalent. Any switching means (not shown) selectively connecting any point on conductor 36 with any point on conductor 34 or conductor 39 could be used in lieu of or in addition to switch 41 if desired for the purpose controlling operation of plate 28 from a location within the apartment remote from chime 31. However, the canopy type switch with a pull cord is admirably adapted to direct

and ornamental mounting on the chime mechanism and it eliminates the necessity of access to concealed wiring in the building.

What is claimed is:

- 5 1. Door signal mechanism comprising a casing adapted for mounting adjacent an entry door, a push button switch mounted on the front of the casing, said casing having a window aperture adjacent its top, a vertically mounted solenoid coil in the upper part of the casing immediately behind the window, an armature reciprocable in the coil and normally depending gravitationally out of the coil, an L-shaped, non-magnetic an-15 nunciator plate fixed to the armature and having its major body portion co-extensive with said coil and provided on one face with indicia visible through the window in the casing when the armature is in its lowered position, and further having other indicia below the firstmentioned 20 indicia, and adapted to be raised to a position of visibility through said window by movement of the armature from its lowered position a conductor connecting one pole of the push button switch with one end of the solenoid, the other end of said solenoid adapted for connection with 25 an electrically operable chime signal means of greater electrical resistance than said solenoid coil, and a conductor connected to the remaining pole of the push button switch and adapted for 30 connection with a source of electrical energy for said chime signal means.

- 35 2. Door signal installation comprising an electrically operable chime mechanism, a source of electrical supply suitable for actuating the chime mechanism, a push button casing, a push button switch in the casing having a window aperture in the front wall, a vertical solenoid coil mounted in the casing directly behind the center of said window and having appreciably lower resistance than said chime mechanism, conductor means connecting the poles of the push button switch in series with the solenoid coil, chime mechanism and the source of electrical supply whereby operation of the push button switch normally actuates the electric chime mechanism and only weakly energizes the solenoid in the casing, a switch selectively operable for short-circuiting the electric chime mechanism whereby the chime mechanism is rendered inoperative and the solenoid coil is strongly energized, said casing having 45 a window in front of the solenoid, a non-magnetic plate disposed within the casing intermediate said window and said solenoid and having superposed indicia selectively visible through the window as said plate is raised and lowered, said plate at all times concealing the coil and substantially closing the window, and an armature operable by the solenoid coil and carrying said plate.

- 50 3. Door signal means comprising a hollow push button casing, a push button mounted on the lower end of the casing, a solenoid coil suspended vertically in the upper portion of the casing, a transverse window in the casing intermediate the top and bottom of the solenoid coil, a plate vertically shiftable disposed principally in parallel relation with the front of the casing and forming constant a closure for the window, an armature in the coil and having said plate rigidly secured thereto and in substantially coextensive relation 55 to the coil whereby the plate is raised along the window upon strong energization of the coil, said plate having superposed indicia selectively visible through the window in the casing as said plate is raised and lowered, and conductor means per-70 manently connecting the solenoid coil in series

with one pole of the push button switch, the other pole of the push button switch adapted for connection with one terminal of a source of electrical energy.

4. Door signal means comprising a hollow push button casing having a transverse window, a push button mounted on the lower end of the casing, a solenoid coil suspended vertically in the upper portion of the casing, a plate disposed principally in parallel relation with the front of the casing and extending at all times across the window, an armature in the coil and having said plate rigidly secured thereto whereby the plate is raised and lowered materially between limits upon strong energization and relative deenergization of the coil, said plate having superposed indicia selectively visible through the window in the casing as said plate is raised and lowered by strong energization and gravity respectively conductor means permanently connecting the solenoid coil in series with one pole of the push button switch, a branch circuit conductor and a glow lamp in series therewith mounted within the casing for illuminating said plate, the other pole of the push button switch adapted for connection with one terminal of a source of electrical energy.

5. A door signal control comprising a casing having a window therein, a push button switch mounted in said casing, a solenoid coil of low electrical resistance mounted in depending and closely spaced relation behind the window in said casing, a vertical armature in said coil, a light weight non-magnetic plate constantly disposed intermediate said window and said coil and provided with an integral bracket fixed to said armature, means limiting gravitational descent of said plate and armature, the plate having indicia identifying the householder disposed in registry with said window when the plate rests on said limiting means, said plate having the legend "out" disposed below and in non-registry with the window in said position of the plate, an electrical connection between one terminal of the push button and one end of said coil, the remaining terminal of said push button and the remaining end of said coil being adapted for connection into a series electrical circuit with a chime mechanism and an electrical power source, and a switch for selectively establishing a shunt circuit around said chime mechanism.

6. In combination an electrical chime mechanism, a canopy type switch connected across the terminals of said chime mechanism, a power source having one terminal thereof electrically connected to one terminal of said chime mechanism, a casing, a pair of electrical conductors connected to the remaining terminals of said power source and said chime mechanism respectively and entering said casing, a push button and a solenoid coil of lesser electrical resistance than said chime mechanism mounted in the cas-

ing and connected in series with the ends of said conductors, an alternative visual signal member shiftably mounted in said casing, and an armature in said coil and connected to the signal member for directly shifting the said member to selected positions of visibility as the coil is strongly energized and relatively deenergized.

5 7. In combination a casing having a window therein, a plate movable across said window and bearing indicia alternately visible through the window as the plate is disposed at opposite limits of its movement, a glow lamp in the casing for illuminating the indicia, an electrical chime mechanism remote from the casing, a switch member for selectively establishing a shunt circuit across the terminals of said chime mechanism, a power source having one terminal thereof connected with one terminal of said chime mechanism and also with one terminal of said glow lamp in the casing, a pair of electrical conductors connected respectively to the remaining terminals of said power source and said chime mechanism, said conductors being extended to said casing, a push button and a solenoid coil of lesser resistance than said chime mechanism disposed in the casing and connected in series with the ends of said conductors, a branch connector connected intermediate the coil and the push button and to the remaining terminal of the glow lamp, and an armature disposed in the solenoid coil and rigidly connected with said movable plate.

10 15 20 25 30 35 40 45 8. In combination a solenoid coil, a push button switch closely spaced in vertical relation thereto, a shallow casing covering and supporting said coil, and switch and having a window immediately in front of the coil, an armature reciprocable in the coil as said coil is energized and de-energized, and an L-shaped non-magnetic indicia plate secured to the armature and shiftable thereby to alternately expose selected areas of one face thereof through said window, said plate at all times covering the entire window and the coil behind said window, indicia on said selected areas, and means to energize the coil.

Certificate of Correction

November 8, 1949

Patent No. 2,487,541

WILLIAM C. GUSTIN

It is hereby certified that errors appear in the printed specification of the above numbered patent requiring correction as follows:

Column 4, lines 36 and 37, strike out the words "having a window aperture in the front wall" and insert the same in line 35, after "casing" and before the comma; lines 64 and 65, for "a plate vertically shiftable" read *a vertically shiftable plate*; and that the said Letters Patent should be read with these corrections therein that the same may conform to the record of the case in the Patent Office.

Signed and sealed this 28th day of February, A. D. 1950.
